US00D722114S

(12) **United States Design Patent** (10) **Patent No.:** **US D722,114 S**
Jo (45) **Date of Patent:** **** Feb. 3, 2015**

(54) **LABEL**

- (71) Applicant: **Jae Chul Jo**, Seoul (KR)
(72) Inventor: **Jae Chul Jo**, Seoul (KR)
(73) Assignee: **Hajung Bitech Co., Ltd.**, Gimpo-Si (KR)
(**) Term: **14 Years**
(21) Appl. No.: **29/487,032**
(22) Filed: **Apr. 4, 2014**
(51) LOC (10) Cl. **19-08**
(52) U.S. Cl. **USPC D20/23; D20/29**
